UNITED STATES PATENT OFFICE.

HORACE M. STAGGS, OF DALLAS, TEXAS.

AIR-LIFT PUMP.

Application filed June 30, 1927. Serial No. 202,555.

This invention relates to air lift pumps. and it comprises a pump particularly adapted for ejecting oil or water from deep wells by means of pneumatic pressure; said pump including a regulating valve disposed within the well casing near the bottom thereof, tubing strings attached to the regulating valve, means for admitting water or oil within the tubing, and means permitting the application 5 of pneumatic pressure through the valve to the oil or water within the tubing to eject the same; all as more fully hereinafter set forth and as claimed.

It is customary to force liquids, such as oil 15 and water, from deep wells by means of air pressure. Apparatus for effecting this ejection are termed air lifts, and many arrangements have been proposed for utilizing the principle. Some are quite complicated in 20 construction, and hence are objectionable because of the difficulty experienced in maintaining the parts in condition. Others require the use of a plurality of concentrically disposed pipes, and are costly to install. 25 Still other systems necessitate the application of an excessive initial air pressure, and are therefore objectionable since the auxiliary apparatus is unduly expensive.

It is the purpose of the present invention 30 to provide an air lift pump, simple in construction, requiring a minimum of parts, and highly efficient in its utilization of air, thereby meeting the urgent requirements of low initial cost and operation. A practical embodiment of the invention is illustrated on 35 the accompanying drawing, wherein

Fig. 1 is a longitudinal view, partially in elevation and partially in cross-section, of the upper portion of a deep well with a pump installed therein;

Fig. 2 is a view similar to Fig. 1, showing the lower portion of the well;

Fig. 3 is a longitudinal cross-sectional view of a regulating valve; and

Figs. 4, 5, and 6 are transverse cross-sectional views of the valve shown in Fig. 3, taken respectively on the lines 4-4, 5-5 and 6-6.

As shown in Figs. 1 and 2, the water or oil 50 level 10 is reached by means of a drilled hole, defined by a metallic casing 11, which is formed of a plurality of joined sections of pipe. The upper end of the casing 11, which is disposed at about the ground level, has secured thereto a header 12 provided with an inlet port 13, by means of which air under

pressure is delivered from a suitable source, (not shown), to the liquid to be raised.

A pipe or tubing 14, disposed within and in concentric relation to the casing 11, projects through the header 12, and is likewise provided with a smaller header 15 having an outlet port 16 for the liquid forced to the surface by the air entering through the port 13. The header 15 is provided with a centrally 60 disposed aperture for the reception of a rod 17 that is adapted to be reciprocated by a suitable source of motive power, not shown. The rod 17 terminates within the tubing 14, and is there attached to a chain or flexible 65 link 18 which extends to a plunger or weight 19, by means of which an air lift regulating valve may be actuated.

The tubing 14 extends nearly to the bottom of the well, where it terminates in a regulating valve, indicated generally by the reference numeral 21, to which it is secured by a suitable means, such as a screw-threaded connection (Fig. 3). The lower end of the valve is formed with a concentric recess 23 which 70 is adapted to receive another section of tubing 24 that extends to the liquid level and which is provided with a ball valve 25 at its lower extremity to control the entrance of liquid. The space between the casing 11 and 75 the lower tubing section 24 is sealed by means of a packer 26, which is positioned just below the valve 21, and which prevents the passage of fluid in the casing upwardly and exteriorly 80 of the valve 21.

The regulating valve serves to divert air or 85 gas introduced into the upper portion of the casing through the port 13 into the lower section of the tubing 24 to effect its lifting operation on liquid contained therein. For this 90 purpose, the valve 21 is formed with closable 95 passages, as best illustrated in Fig. 3.

As there illustrated, the valve 21 is formed with a screw-threaded recessed portion 27 for the reception of the upper tubing section 14. Secured to the floor 28 of the portion 27 is a 100 guide 29, provided with a centrally disposed aperture 31 for the reception of a valve stem 32 which also projects through the floor of the member 21. The guide 29 is partially 105 surrounded by a flanged telescoping sleeve member 34 to which is secured the upper extremity of the stem 32. A coiled spring 35, disposed between the flange 36 on the member 34 and the guide 29, serves to force the sleeve 110 34 upwardly.

Beneath the guide 29 is an enlarged duct

37, provided with a lateral port 38 at its upper end, a valve seat 39 in its mid portion, and a second lateral duct 41 adjacent its lower portion, extending to the outer surface of the member 21. The duct 37 is closed below the port 41 by means of a plug 42, which is advantageously a separate part positioned in the member 21. The valve stem 32 terminates adjacent the valve seat 39 in a valve 43, and, 10 by virtue of the pressure of the spring 35, this valve 43 normally rests on the seat 39, thereby closing the passage extending from the lateral port 41 and the oppositely extending port 38.

15 The port 38 does not extend to the outer surface of the valve member 21, but terminates in a longitudinally extending chamber 45, sealed from the recess 27 by means of a wall 46, and extending below the plug 42. At this region, the chamber 45 merges 20 into a transversely disposed port 47 which extends through a wall 48, spacing the chamber 45 from the duct 37, into a concentrically disposed recess 49 that extends from below 25 the plug 42 to the bottom of the valve 21.

The recess 49 is provided with a screw-threaded portion 51, in which is disposed a length of pipe or tubing 52, that projects downwardly through the packer 26 nearly to the ball-valve 25 positioned in the tubing 24. The lower portion of the valve 21 is counter-bored to form a recess 53, and is also provided with screw threads 54 for the reception of the tubing 24, which extends downwardly, in the manner previously described, concentrically of the pipe 52.

As shown in Figs. 4, 5, and 6, the valve 21 is drilled in a longitudinal direction at a suitable number of points to provide apertures or vents 55 which permit the flow of mixed gas and liquid from the lower tubing section 24 to the upper section 14 and thence out of the well.

45 Air or gas entering through the port 13 into the casing 11 flows downwardly until it meets the packer 26, when it is diverted through the port 41 into the duct 37 in the valve 21. Here it is met by the valve 43, resting on the valve seat 39, which prevents 50 passage into the chamber 45 through the lateral port 38. In operation, however, the rod 17, disposed at the upper end of the well, is constantly reciprocated, thus moving the weight 18 up and down, and causing it to strike intermittently and periodically on the sleeve member 34. The force of the blow is sufficient to drive the valve stem 32 downwardly against the force exerted by the coiled spring 35, thus effecting a periodic 55 opening of the valve 43, and permitting the passage of compressed air from the casing 11 into the chamber 45. Air admitted into this chamber flows downwardly, by virtue of its pressure, through the lateral port 47 and the 60 pipe 52. It is there ejected into the liquid

from the well which has entered the tubing 24 through the ball-valve 25 during the period when the valve 43 was closed. As the air, now released from its pressure, rushes upwardly to escape into the atmosphere, it 70 mingles with the liquid, thereby lifting it through the apertures 55 into the upper tubing sections 14, and thence out of the well through the port 16.

It will be noted that the regulating or control valve 21 is simple in its construction, and has few moving parts to become broken. Should the vents 55 be clogged by particles of sand, the pressure may be momentarily reversed, and compressed air directed downwardly through the tubing 14 to dislodge any grit that has collected. The liquid is forced to the surface by means of periodic impacts of compressed air, which may occur at such frequent intervals as to make the delivery 85 practically continuous. The simplicity of the valve construction permits of rapid operation, which is often advantageous, and is also possible with this invention because of the elimination of back pressures that otherwise 90 would increase the time factor of operation.

There is practically no back pressure exerted on the valve 43, and hence a slight hydrostatic pressure exerted by the liquid in the well permits the casing 24 to be filled 95 through the valve 25 in a minimum amount of time. This feature is of importance, as it permits the application of the air lift principle to small wells, wherein the hydrostatic head is often very small.

In working with such small wells, the volume of fluid delivered and the pressure may be so low as to render the application of air pressure alone through the port 13 impractical. When this condition obtains, it 105 is still possible to eject fluid from the well by operating under vacuum instead of pressure. A reduced pressure or vacuum is applied to the port 16, thereby exhausting the air in the tubing 14 and 24 and the pipe 52. The air entrapped in the casing section 11 below the packer 26 and the liquid level 10 is thus permitted to expand, forcing fluid through the ball-valve 25 and so out of the well. When operating under vacuum, it is unnecessary to 110 actuate the regulating valve 21, the closure of the valve 43 preventing the ingress of air that would break the vacuum. The well may be pumped both with pressure or vacuum, by providing a suitable control valve on the port 115 16. Under certain conditions, it is desirable to operate alternately; the pressure in the casing 11 being built up while blowing with air, and then being utilized in the manner just described. The alternate methods of operation are possible without change in the apparatus, since the passages for air extend from the top of the well to the bottom thereof.

The invention has a further advantage in 120 that it eliminates a separate tubing for con-

ducting the air down to the point of application. The casing itself serves this purpose, while the upper tubing sections are sufficient for the discharge of both liquid and spent air.

5 As the casing is relatively large in comparison to the air tubings heretofore employed, this feature possesses the further advantage of decreasing the frictional losses attendant on the use of pipes of small diameter. Obviously, the embodiment illustrated is susceptible of modifications without departing from the principles of the invention. Thus, a rigid link could be connected between the rod 17 and the valve sleeve 34, but the construction shown is preferred, as it eliminates the possibility of shaft distortions during use.

What I claim is:

1. An air lift comprising a well casing, a regulator valve disposed in the casing, tubing connected to opposite sides of the valve, a packer disposed below the valve, an air delivery pipe extending downwardly from the valve in the tubing, a passage extending from the outer surface of the valve to the pipe, a closure member in said passage, means for operating said closure member, and means permitting the passage of fluid from one tubing section to the other.

2. An air lift comprising a well casing, a regulating valve disposed in the casing, a tubing extending from the upper portion of the well to the valve and terminating therein, a tubing extending from the lower portion of the valve downwardly adjacent the bottom of the casing, a valve disposed at the lower ex-

tremity of the lower tubing, a packer disposed between the casing and the lower tubing to seal the space therebetween, a pipe extending downwardly from the valve within the lower tubing, means for admitting compressed air to the upper portion of the casing above the packer, a passage extending from the casing through the valve to the pipe, means for periodically opening and closing the passage to admit air from the casing to the pipe, and means permitting the flow of fluid from the lower tubing to the upper tubing under the influence of the air so admitted.

3. A regulator valve for air lifts comprising a substantially cylindrical member, a centrally formed aperture within the member, a valve seat formed on the walls of the aperture, a duct formed in the member below the valve seat and directly connecting the aperture with the exterior surface of the member, a valve for the seat, resilient means for normally holding the valve on the seat, an enclosed chamber formed in the member, and provided with a wall spacing it from the aperture, a passage through said wall above the valve seat connecting said aperture with said chamber, a centrally disposed recess formed in the member below the aperture, a passage extending from the chamber to the recess, and a plurality of vents formed in the member permitting the passage of fluid from one side of the member to the other.

In testimony whereof, I have hereunto affixed my signature.

HORACE M. STAGGS.
